W. HARROP.
SPOOLER GUIDE AND YARN TENSIONER.
APPLICATION FILED MAR. 14, 1918.

Patented Sept. 17, 1918.

UNITED STATES PATENT OFFICE.

WILLIAM HARROP, OF NEW BEDFORD, MASSACHUSETTS.

SPOOLER-GUIDE AND YARN-TENSIONER.

1,279,336.

Specification of Letters Patent. Patented Sept. 17, 1918.

Application filed March 14, 1918. Serial No. 222,354.

To all whom it may concern:

Be it known that I, WILLIAM HARROP, a citizen of the United States, residing at New Bedford, in the county of Bristol and State 5 of Massachusetts, have invented certain new and useful Improvements in Spooler-Guides and Yarn-Tensioners, of which the following is a specification, reference being had to the accompanying drawings.

10 This invention relates to spooling or winding machines, and particularly to the means whereby the yarn is guided and tensioned as it passes from the cop or bobbin to the spool on which the yarn is being wound.

15 The general object of the invention is to provide improved means for guiding or tensioning the yarn in its passage.

A further object is to provide means 20 for properly tensioning the yarn as it comes from the bobbin or cop, such means being so formed that the tension may be regulated or controlled.

A still further object is to provide means 25 whereby the tension on the yarn may be automatically increased or decreased as the size of the yarn package or wrapping of yarn on the spool increases or decreases, and to provide means whereby the tension of the yarn may be regulated or controlled so 30 as to suit the size and build of the yarn package and the speed at which the yarn is being wound.

Still another object is to provide an automatic tensioning device which will cause 35 more tension to be placed on the yarn when the package is small and winding slowly and which will place less tension on the yarn when the package increases in diameter and is winding more rapidly, and in this connection to provide a tensioning device which is attachable to the ordinary "slub catcher" and yarn guide with which machines of this character are ordinarily equipped.

Other objects will appear in the course 40 of the following description.

My invention is illustrated in the accompanying drawings, wherein:

Figure 1 is a side elevation of my im-

proved yarn tensioning mechanism, the rails 10 being in section; 50

Fig. 2 is a front elevation of the yarn guide and allied tensioning weight;

Fig. 3 is a side elevation of the construction illustrated in Fig. 2;

Fig. 4 is a perspective view of the tensioning weight.

Referring to these figures, 10 designates a longitudinally extending guide rod which is disposed adjacent to the spools 11 upon which the yarn is to be wound, this guide 60 rod being operatively connected to the lifting rods (not shown) of any usual or suitable character. Mounted upon the rod 10 and disposed in front of each of the spools 11 is the usual thread guide and slub catcher 65 which comprises clamping members 12 and 13, the clamping member 12 being rearwardly extended as at 14 and carrying a lower fixed longitudinally extending jaw 15, the upper edge of which is horizontal and 70 flat. The rearward extension 14 is provided with ears 16 between which is pivoted the shank 17 of a jaw 18 coacting with the jaw 15, the yarn or thread passing between these jaws 15 and 18. The shank 17 is 75 formed with a tongue 19, which extends out over the guide rod 10 and urging the shank 17 upward and the jaw 18 into contiguity with the jaw 15 is a spring 20, whose tension is controlled by a screw 21. 80

The clamping member 13 confronts the clamping member 12 and these clamping members are provided with semi-circular seats for the rod 10 and the clamping member 13 has an upward extension 22 which at 85 its upper end is extended rearward and then downward as at 23, this downwardly extended portion being laterally elongated as at 24. This portion 22 and 23 is not found upon the yarn guides and slub catchers 90 ordinarily used but is part of my invention.

Coacting with the keeper 22 as it may be termed is the tensioning weight 25. This is of metal and has a slightly rounded under 95 surface 26 which rests upon the guide rod

10. The upper surface is upwardly and laterally curved and is bounded by an upwardly extending lug 27 whose outer face is slightly beveled and which intersects a 5 longitudinally extending lug 28, the under face 29 of which is inclined downward toward the body portion of the weight and intersects a downwardly extending shoulder 30. This tensioning device is inserted with 10 its body beneath the keeper 22 and with the lug 27 bearing against the confronting face of the keeper and the lug 28 disposed beneath the tongue 19. The intersection of the surface 30 and the surface 29 forms the 15 fulcrum of this tensioning weight, this fulcrum bearing upon the adjacent corner of the clamping members 12 and 13. It will be obvious now that because of the beveled face 29, the body 25 may lift within certain limits and it is obvious that the power 20 required to tilt the body will vary as the power is applied nearer to or farther from the fulcrum point and, therefore, that the weight or downward pressure of this body 25 upon the rod 10 will vary as the point of application of the weight is nearer to or 25 farther from the fulcrum point.

The bobbin or cop from which the yarn is to be withdrawn is mounted below the rod 30 10 in any suitable or usual manner.

In the practical use of this invention, the 35 yarn *a* is carried from the cop (not shown) over the rod 10 between the rod and the automatic weight lever 45 and thence between the jaws 15 and 18 to the spool 11. Now it will be obvious that as the yarn is wound upon the spool 11, the diameter of the spool 11 or of the yarn package will 40 gradually increase and hence the surface speed will increase. Under these circumstances, it is desirable that less tension be applied to the yarn as it passes through the spool than is applied when the yarn or thread package is relatively small in diameter. This automatic regulation of the tension is secured by means of the weight 25 for as the diameter of the yarn package 11 increases, the yarn *a* will be shifted gradually outward from a point relatively near to 45 the fulcrum of the weight to a point relatively distant from the fulcrum of the weight. At the point adjacent the fulcrum the weight exerts relatively considerable power; that is, bears relatively heavily upon 50 the yarn and then as the size of the package 11 increases, the yarn will be shifted nearer and nearer to the end of the weight and, as a consequence, the weight will exert less and less pressure upon the yarn, thus decreasing 55 the tension on the yarn. It will be noted from Fig. 3 that the under face of this weight, that is the face confronting the rod 10, is slightly rounded so as to exert no more

than the desired frictional bearing on the 65 yarn.

It will be noted that by means of the tongue 19, the jaw 18 may be separated to its full extent from the jaw 15 and that inasmuch as this tongue 19 extends over the lug 28, a depression of this tongue will force 70 downward upon the lug 28, thus causing the weight to rock upon its fulcrum and lift entirely free from the lifting rod 10. This permits the confronting faces of the jaws 15 and 18 and the confronting faces of the rod 75 10 and weight 25 to be cleaned simultaneously as it is necessary from time to time to do. Of course it is understood that means are commonly provided for limiting the extent to which the jaws 18 and 15 are forced 80 toward each other by the spring so as to thereby regulate the space between the jaws in conformity with the work being done.

Having described my invention, what I 85 claim is:

1. In a machine for spooling yarn, a rod over which the yarn passes, and means for tensioning the yarn comprising a relatively elongated weight resting upon and extending parallel with the rod and between which 90 weight and the rod, the yarn passes, the weight having a fulcrum adjacent one end upon which fulcrum the weight bears at all times.

2. In a machine for spooling yarn, a rod 95 rotating yarn package, a rod over which the yarn passes to the yarn package, and means for tensioning the yarn comprising a relatively elongated weight resting upon and extending parallel to the rod and between 100 which rod and weight the yarn passes to the package, the weight being fulcrumed adjacent one end, the fulcrum point on said weight being approximately opposite the axis of the yarn package whereby as the 105 yarn package increases in diameter and the path of travel of the yarn shifts laterally upon the rod and away from the fulcrum, the weight will exert less tension upon the 110 yarn.

3. In a machine for spooling yarn, a rod over which the yarn passes, a member mounted upon the rod and having an upwardly extending portion arching over the rod transversely thereto, and a weight loosely disposed between the rod and the upwardly extending portion and rocking upon a fulcrum beneath the overarching portion.

4. In a yarn spooling machine of the character described, a rod over which the yarn passes, coacting clamping members mounted upon the rod, one of said clamping members carrying a fixed and a movable jaw between which the yarn passes, the movable jaw having a tongue extending outward over the 125 clamping members, the other of said clamp-

ing members having a portion offset with relation to said tongue and arching over the rod, and means for tensioning the yarn passing over the rod comprising an elongated weight fitting within the overarching portion of said clamping member, said weight having a body bearing upon the upper face of the rod and having a portion extending over the clamping members and beneath the tongue, and an upwardly extending lug bear-

ing against the face of the overarching portion, said weight being fulcrumed upon the clamping member.

In testimony whereof I hereunto affix my signature in the presence of two witnesses. 15

WILLIAM HARROP.
